TIME RECORDER

Dana L. Vickery, Gardner, Mass., assignor to Simplex
Time Recorder Company, Gardner, Mass., a corporation of Massachusetts

Filed July 26, 1965, Ser. No. 86,284

Term of patent 14 years

(Cl. D42—7)

FIG. 1

FIG. 4

FIG. 1 is a perspective view of a time recorder, showing my new design;

FIG. 2 is a plan view of the time recorder,

FIG. 3 is a front elevation of the time recorder, and FIG. 4 is an end elevation of the time recorder, as observed from the left end in FIG. 3.

The right end of the time recorder, not shown, is substantially a mirror image of the left end as seen in FIGS. 1 and 4; while the rear and bottom of the recorder are substantially plain and unornamented.

I claim:

The ornamental design for a time recorder, as shown and described.
